ROTATING WATER SPRAYING HOOP FOR RECREATIONAL USE

John M. Darling, Rte. 1, Loveland, Colo.

Filed Feb. 15, 1962, Ser. No. 68,850

Term of patent 14 years

(Cl. D34—5)

FIG. 1 is a perspective view of a rotating water spraying hoop for recreational use showing my new design; and

FIG. 2 is a top plan view thereof.

I claim:

The ornamental design for a rotating water spraying hoop for recreational use, as shown.
